WALL STRUCTURE

Anthony G. Siebenlist, Milwaukee, Wis., assignor
to Milcor Steel Company, Milwaukee, Wis., a
corporation of Delaware

Application June 9, 1938, Serial No. 212,681

11 Claims. (Cl. 72—115)

This invention relates to wall construction and particularly to the construction of a rigid metal framework suitable for attaching metal lath and plaster or similar wall surfaces for partitions and the like.

It is a purpose of the invention to effect a light and rigid metal framework for partitions, walls and the like in which spaced parallel track or runner members are connected by transverse members in an improved manner.

A further purpose is to effect improved connecting means for joining mutually transverse wall frame members, and particularly for joining the ceiling and floor runner or track members to the vertical studs of partition walls.

A further purpose is to provide connecting means for partition wall frame members and the like with improved convenience of assembly of the various parts.

A further purpose is to provide an improved coupling construction for locating and spacing wall studs relative to one another or to a floor or ceiling, or relative to track or runner elements, and particularly a coupling construction which is operative to rigidly fix the position of the stud without the use of wiring or similar expedients.

A further purpose is to effect an improved wall structure in which intersecting track or runner elements and stud elements are coupled or fixed together at their various intersections in a manner which permits the same sectional form for both the intersecting runner and stud elements, and permits the same form of coupling members to be used at all intersections, whereby to simplify manufacture, construction and assembly.

A further purpose is to provide a coupling device for fixing the position of the ends of metal studs which permits of use for coupling the stud directly to another wall, such as a floor or ceiling, or permits of coupling the stud to track or runner sections at one or both ends, by the means of the same form of coupling device.

A further purpose is generally to simplify and improve the construction, operation and assembling of wall or partition frames, and particularly of means for rigidly positioning and connecting the various elements or members of the frame.

The invention comprises the construction and combination of parts as herein illustrated, described and claimed, and such modifications of the structure illustrated and described as may be equivalent to the claims.

The same reference characters have been used

to identify the same parts throughout, and in the drawings:

Figure 1 is a perspective view of a portion of a wall frame incorporating the invention in one of its aspects.

Figure 2 is a horizontal section of the same wall frame taken approximately along plane 2—2, 2—2 of Fig. 1.

Figure 3 is a left side elevation of the lower portion of the structure of Fig. 1, partly in section along line 3—3 of Fig. 2.

Figure 4 shows a perspective view of a connecting member used in the structure shown in Fig. 1, in a form prior to assembly in the frame.

Figure 5 is a partial perspective view of some of the parts of the frame of Fig. 1 in an intermediate stage of assembly.

Figure 6 shows a perspective view of a portion of wall frame of modified construction, also incorporating the invention, one of the connector members being shown only partly assembled in the frame.

Figure 7 is a horizontal section of the wall frame of Fig. 6, but fully assembled, taken approximately along the plane 7—7, 7, 7 of Fig. 6.

Figure 8 is a left side elevation of the portion of wall frame shown in Fig. 6, but fully assembled, and partly in section along line 8—8 of Fig. 7.

Figure 9 shows a perspective view of a connector clamp element used in the structure of Fig. 6.

The wall structure of Fig. 1 includes members comprising a horizontal ceiling runner or track 10, vertical studs such as 11 and a horizontal floor runner or track 12. Each of these members are preferably channel members of the same cross section form and size, a preferred form being that shown for the members 11, 12 in Figs. 2, 3. In each of the members there is a central web portion such as 13 rigidly connecting side channel portions such as 14, 15 which are inwardly open. It will be understood that in partition constructions the runners 10, 12 will be as long as required and that there will be a number of studs such as 11 suitably spaced.

The runner members 10, 12, Fig. 1 are each rigidly fixed in position relative to the stud members 11 by the means of the similar coupling members such as 16, 16 and the similar locking members, such as 17, 17.

Coupling members 16 may be initially formed as shown in Fig. 4. The members include the spaced arms or projecting portions 18, 19 integrally formed with an intermediate portion 20. At the junction of each arm with the intermediate

portion there are outwardly formed portions such as 21, 22, and each arm also has outwardly formed portions such as 23, 24. In this initial form the intermediate portion 20 is bent sufficiently that the outwardly formed portions 20, 21 will enter between the inner edges, such as the edges 14a, 15a, Fig. 5, of the channeled runner members. The intermediate portion 20 is provided with apertures 25, 26 for suitable fasteners, such as the nails 27, 27, Fig. 3.

In the assembled structure the coupling members 16 serve to locate the studs relative to the runners at each joint, the outwardly formed portions 21, 22 engaging within the channel portions 14, 15 of the runner members, as shown in Fig. 3, and the outwardly formed portions 23, 24 engaging within the channel portions 14, 15 of the stud members as shown in Fig. 2. To effect this assembly of the members the connecting member 16, while in the form shown in Fig. 4, is positioned for the outwardly formed portions 21, 22 to stand between the inner channel edges 14a, 15a as previously mentioned, and the intermediate portion 20 is then straightened out, as by hammer blows, to simultaneously spread the portions 21, 22 into rigidly engaged positions in the side grooves of the channel member, and bringing the arms 18, 19 to substantially parallel position, as shown in Fig. 5. At this time the runner member and connecting member may be fixed in the desired runner member position by the means of nails or suitable fasteners such as 27, Fig. 3, but the length of the intermediate portion 20 may be sufficient, if desired, for the studs to be rigidly fixed in position merely by expanding the portions 21, 22 into the channel grooves, and without the use of the fasteners 27. In such case the runners may be fixed in position independently of the connectors 16 and by any suitable means.

When each of the members respectively forming the upper runner 10 and lower runner 12 have been positioned as described, with connecting members 16 positioned at each point where a stud joint is intended, the channel members forming the studs may be sprung or forced sidewise over the outwardly formed portions 23, 24 on the arms 18, 19, the outwardly formed portions and arms of the connectors then loosely engaging between the channel portions of the studs, as shown in Fig. 5. The function of the locking members 17 is to rigidly engage and lock the arms of the connecting members with the stud channels.

Locking members 17 are formed with a relatively narrow end 17a. The outward forming of the arm portion 23, 24 provides inner grooves 23a, 24a, Fig. 2, within which the narrow end of the locking member may be positioned, as shown in Fig. 5. The narrow end 17a is joined with a wider end 17b by a tapered portion 17c of increasing width, and as the locking member is forced into further engagement to the position shown in Fig. 3, the arms 18, 19 are spread outwardly to rigidly engage with the channel member, as shown in Fig. 2. The locking members 17 may, if desired, be formed with a laterally projecting lug portion 17d, to operate as a handle, or as an abutment, to assist in positioning or releasing the locking member.

Following the positioning of the connecting and locking members as described the runners and studs are rigidly retained and locked against movement relative to one another or to the ceiling and floor, and any suitable form of metal lath or other suitable base for wall surfaces, not shown,

may be attached thereto in any suitable well known manner as, for example, by wiring.

The construction shown provides sufficient rigidity that the various channel and coupling members may be made of relatively thin and light sheet metal, and the weight may be further reduced by removing portions of the material of the channel member connecting webs 13 to provide spaced apertures, as shown. The material may be removed in any desired pattern provided it does not unduly decrease the strength of the channel member in the plane of the web, and if desired the removed material may be of a form to be utilized for locking members. Thus the material punched from the web apertures shown in the drawings, Fig. 1, is usable for the purpose of making the locking members 17.

The modified construction shown in Fig. 6 includes studs such as the stud 11A, and runners, such as the runner 12A, which are of substantially the same side channeled construction as the runners and studs of the construction of Fig. 1, but differ in the connecting web portions as to the form of the openings and in the provision of strengthening ribs such as 30, 30 which are struck up from the plane of the web. The connectors such as 16A of the structure of Fig. 6 are also similar to those of Fig. 1, except for being narrower both in the arm portions such as 18A, 19A and in the intermediate portion 20A connecting the arms, but still providing outwardly formed portions such as 21A, 22A at the junction of the arms with the intermediate portion, also the outwardly formed arm portions such as 23A, 24A, these outwardly formed portions cooperating to engage in the inner channel grooves of the studs and runners in the same manner as for the couplings of Fig. 1, previously described. Fasteners such as 27A, 27A may be used, as for the frame of Fig. 1.

Locking members 31, 31 for the structure of Fig. 6 are materially different in form than for the structure of Fig. 1. The locking members 31 cooperate individually and separately with the different arms 18A, 19A of the connector 16A, to lock the arm into rigid contact within the adjacent grooved channel edge of the stud. To effect the locking action, in this instance, the locking members 31 are provided with a wedge portion 31a, an abutment portion 31b, and connecting portions 31c, 31d. The wedge portion 31a, when the locking member is in place, engages inside the internal groove associated with the outwardly formed arm portions 23A or 24A, as the case may be and the abutment portion 31b engages outside the channeled edge of the stud, as more particularly shown in Figs. 7, 8; the connecting portion serving to bind the connector arm and channeled portion of the stud rigidly together. In positioning the locking members 31 the member is first hooked around the channeled edge of the stud at a point outside the zone occupied by the arm of the connector member 16a, somewhat as indicated by the intermediate position of the assembly shown for the left hand locking member 31 in Fig. 6, and having been suitably positioned is then forced downwardly, as by hammer blows, to effect locking engagement of the wedge portion 31a and abutment portion 31b with the associated stud and connector parts, as shown in Figs. 7, 8. In order that one form of locking member 31 may be usable for either side of the stud, the wedge portion 31a is formed, as shown in Figs. 8, 9, with angularly disposed wedging sur-

faces at both ends, although an angular portion at the one end only would be sufficient for either edge of the stud.

The locking means just described has, among other advantages, the advantage of not tending to spread apart the channeled edges of the studs. It operates without setting up any spreading strain on the intermediate web of the studs, and for this reason is a preferred form for many uses.

In any of the described forms the assembly of the stud members with the connecting members may be effected by sliding the studs longitudinally over the arms of the connecting members 16 after the connecting members are fixed with the runners, but this method may require that the stud members be short enough to enter the vertical space, Fig. 1, between the downwardly and upwardly extended arms of the upper and lower connecting members. In such case the studs will be locked in a final position by the locking members 11 or 17A only after the stud has been shifted vertically to substantially equally engage the arms of the upper and lower connecting members.

Any of the various member forms described may, of course, be similarly used where the runners 10, 12 are disposed vertically, and the studs are horizontal.

In still another form of the wall structure one, or both of the runners may be dispensed with, and the coupling members then become locating members which are fixed directly to the adjacent wall by the means of the fasteners which, together with the coupling members, then serve to wholly position the ends of the studs.

It will be noted that in each of the described structures a coupling means is used to join studs and tracks together by a keeper or the equivalent, the arms of the coupling means being forced into engagement with the flanges of the stud and then held in relative position by locking means.

Thus, in the structure of Fig. 1, the inwardly facing surfaces of the longitudinal side or edge flanges of the upper runner or track 10, and also of the lower track 12 present inwardly facing abutments. The coupling means for connecting the tracks to the vertical stud 11 includes, in each instance, a member such as 16, Fig. 3, having keeper means comprising the portions such as 21, 22 respectively engaging the different track abutments, and also having upwardly extended arms such as 18, 19, Figs. 3, 5, engaging the side or edge flanges 14, 15 of the stud. The arms of each connecting member being rigidly spaced apart to fit the stud flanges, the arms and stud flanges are restrained in relative lateral positions by the contact therebetween. Similarly for the structure of Fig. 6, excepting that, in this instance, locking members 31, 31 are used instead of the locking members such as 17 of Fig. 1.

What is claimed is:

1. A wall construction comprising transversely positioned channel members and a unitary coupling member therefor having extended arm portions each simultaneously engaging with channel portions of each of said channel members.

2. A wall construction comprising transversely positioned channel members and a coupling member having arm portions each simultaneously engaging with channel portions of each of said channel members, said coupling member having a connecting portion joining the similar

ends of said arm portions and providing an aperture for a fastening means.

3. In a wall construction the combination of 5 mutually transversely positioned channel members each having spaced side portions connected by a web portion, and a unitary connector having extended parallel portions and an intermediate portion joining the corresponding ends of the parallel portions, said intermediate connector portion being positioned between the side portions of one of said channel members and said parallel portions being respectively engaged within the different side portions of the other channel member.

4. In a wall construction the combination of 10 mutually transversely positioned channel members each having spaced side portions connected by a web portion, and a connector having extended parallel arm portions and an intermediate 15 portion joining the corresponding ends of the arm portions, said intermediate connector portion being positioned between the side portions of one of said channel members and said parallel arm portions being respectively engaged within the different side portions of the other channel member, and fastening means associated with said intermediate connector portion.

5. In a wall construction the combination of 20 mutually transversely positioned channel members each having side portions connected by a web portion, and a connector having extended parallel arm portions and an intermediate portion between the corresponding ends of the arm portions, said intermediate connector portion being positioned between the side channel portions of one of said channel members, said parallel arm portions respectively extending interiorly adjacent the different side portions of the other channel member, and locking means retaining 25 said parallel arm portions in rigid engagement with the last mentioned channel member portions.

6. In a wall construction the combination of 30 mutually transversely positioned channel members each having side portions connected by a web portion, and a connector having extended parallel arm portions and an intermediate portion between the corresponding ends of the arm portions, said intermediate connector portion being positioned between the side portions of one of said channel members, said parallel arm portions extending interiorly between the side portions of the other channel member, fastener means extending through said intermediate connector portion to fix the position of the connector relative to another wall, and locking means 35 associated with said parallel arm portions to fix the position thereof relative to said other channel member.

7. A wall construction comprising a channeled stud including side portions connected by a web portion, and a connector adapted to fix the position of said stud relative to another wall, said connector including extended parallel arm portions and an intermediate portion joining the corresponding ends of the arm portions, said arm portions extending in engagement within the interior surfaces of said stud side portions, and locking means associated with said arm portions to fix the position thereof relative to said interior surfaces.

8. A wall construction comprising a stud having side portions joined by a web portion, said side portions each including a portion angularly disposed relative to the web and an inwardly di-

rected edge portion fixed to the angular portion, whereby to provide for each side portion a longitudinal interior groove, and a unitary connector including an intermediate portion and parallel arms similarly longitudinally extending from opposite ends of said intermediate portion respectively, said arm portions respectively longitudinally engaging different of said interior grooves.

9. A wall construction comprising a runner and a stud manually transversely arranged, said runner and stud each having side portions joined by a web portion, said side portions each including a portion angularly disposed relative to the web and an inwardly directed edge portion fixed to the angular portion, whereby to provide for each side portion a longitudinal interior groove, a connector including an intermediate portion and parallel arms similarly longitudinally extended from opposite ends of said intermediate portion respectively, said opposite ends each providing outwardly formed portions respectively engaging the longitudinal interior grooves associated with the different edges of said runner, said arms each providing outwardly formed portions respectively engaging the longitudinal interior grooves respectively associated with the different edges of the stud, and clamp means

fixing the position of said arms relative to the stud.

10. A wall construction comprising a runner and a stud mutually transversely arranged, said runner and stud each having side portions joined by a web portion, said side portions both for the runner and stud providing inwardly opposed grooves, and a connector including an intermediate portion and parallel arms similarly longitudinally extended from opposite ends of said intermediate portion respectively, said opposite ends respectively engaging within the longitudinal interior grooves respectively associated with the different edges of said runner, said arms respectively engaging the longitudinal interior grooves respectively associated with the different edges of the stud.

11. A stud system for partitions and the like including, in combination, a track presenting inwardly facing abutments, a stud having flanges, and a coupling means for connecting the stud and track including a member having keeper means for engaging said abutments and also having arms carried by said member for engaging the flanges of said stud, and means restraining said arms and flanges in relative lateral positions.
